UNITED STATES PATENT OFFICE.

JOHN M. WASHBURN, OF HARTFORD, CONNECTICUT, ASSIGNOR TO THE MERROW MACHINE COMPANY, OF HARTFORD, CONNECTICUT, A CORPORATION OF CONNECTICUT.

BUCKET FOR USE IN HARDENING FURNACES.

Application filed December 19, 1925. Serial No. 76,396.

The object of my invention is more particularly to produce a new form of bucket which will be less liable to distortion and more durable under the influence of heat and use, and will receive and impart heat more uniformly than buckets which have heretofore been used for similar purposes.

My new form of bucket is especially useful in connection with gas hardening furnaces which are provided with a chain or carrier by means of which the buckets are used in series to convey their contents through a heated chamber and discharge said contents outside thereof and deposit them preferably into a supply of oil or other quenching material.

In the accompanying drawings,

Figure 1, is a side view of a bucket embodying my invention, a part being shown broken away to disclose a back wall in section.

Figure 2, is a front view of the bucket shown in Fig. 1.

Figure 3, is a plan view of the same, and,—

Figure 4, is a reduced scale plan view of a development of a piece of material from which may be made that part of the bucket exclusive of the shank.

Referring to the drawings, the numeral 1, designates a bucket or container to which is secured a suitable shank 2, which, in the form shown, is for the purpose of connecting the bucket with a chain or carrier as is common in gas hardening machines, but, heretofore, the shank for carrying the bucket extended to the bottom thereof, where it was attached, usually by rivets, thus to a considerable degree, preventing even heating of the bottom of the bucket, on account of there being much extra thickness of material at a point near the middle of the bottom thereof. Buckets made in the manner described were supported practically in the center of the bottom, and unsupported elsewhere. Hence, under the influence of heat and use, the bucket material became deformed and cracked and frequent renewals were necessary. To overcome this objection, I support the bucket from two sides or ends, by flanges which are preferably formed integrally with the bottom of the bucket and secured to the shank at a suitable distance away from the bottom of the bucket, which results in a more even distribution of heat and at the same time forms an improved support for the bucket, thereby greatly in-

creasing its durability and usefulness. To this end, the bottom (Fig. 1) of the bucket is provided with the flange forming extensions 3 and 4. Similarly, flanges or walls 5 and 6, are turned substantially at right angles upward from the bottom, and the bucket is also provided with a back wall or flange 7, extending practically at right angles to the same height above the bottom of the bucket. For convenience in construction, the bucket may be made from an integral blank of the developed form shown in Fig. 4, this blank being of any suitable heat resisting sheet material. The back wall 7, may be formed by an extension of flange 5, by an extension of flange 6, or by an extension from both flanges 5 and 6, as shown, it is formed by an extension of flange 5, and is welded at one end to a side wall of the bucket and along one of its edges it is welded to the bottom of the bucket thereby making the bucket practically integral. The extensions 3 and 4, of the bottom are preferably riveted to the shank as shown in Figs. 1 and 2. It will be seen that the bucket is provided with a curb or wall extending about the bottom of the bucket excepting at one of its sides, that side, which may be termed the front side, being preferably left open for the discharge of the articles contained and carried by the bucket.

By virtue of the fact that the front of the bucket is bent downwardly (see Fig. 1) the material at that area is better adapted to resist objectionable warping and splitting when highly heated.

In the construction shown this bucket is made from a single piece of sheet material and the back wall of the curb is cut integrally therewith, folded into position, and welded at one end to a side wall and at the bottom edge to the upper face of the receiving surface.

Having thus described my invention, what I claim is,—

1. A bucket of the class described comprising an integral piece of sheet metal having upright and depending flange sections with the latter converging toward a point of remote support.

2. A bucket of the class described comprising a bottom of uniform thickness merging with substantially the same thickness into upright and depending flange sections with the latter converging toward a point of support

at a substantial distance away from the bottom to facilitate distribution of heat about the latter.

3. A sheet metal bucket comprising a bottom having upright flange sections and intermediate depending flange sections with certain of the upright flange sections extended to form an intermediate upright flange section.

10 4. A metal bucket comprising a bottom having upright flange sections and intermediate depending flange sections with certain of the

upright flange sections extended to form a curb around three sides of the bucket.

5. A bucket of the class described folded into form from a blank of sheet material having an area forming a bucket bottom, opposite end areas forming depending supports, opposite side areas forming respective upright side walls, and an extension of one of the side areas forming an additional side wall.

JOHN M. WASHBURN.
